UNITED STATES PATENT OFFICE.

WILFORD C. MACFADDEN, OF PHILADELPHIA, PENNSYLVANIA, ASSIGNOR TO AT-
WATER KENT MANUFACTURING COMPANY, OF PHILADELPHIA, PENNSYLVANIA,
A CORPORATION OF PENNSYLVANIA.

RADIO SYSTEM.

Application filed January 14, 1924. Serial No. 686,056.

My invention relates to radio systems, and more particularly to a system for receiving radio telegraphic or telephonic signals or messages.

- 6 In accordance with my invention the received signal—or message—representing energy is amplified, at radio frequency, in advance of detection or demodulation, in one or more stages each comprising a radio frequency amplifying tube or thermionic device whose input circuit is tuned and in whose anode circuit is the primary of a radio frequency transformer whose secondary is tuned and loosely coupled to and relatively reversed with respect to the primary, in combination with loss producing means for maintaining the amplifier stable notwithstanding tuning of the input and secondary circuits throughout a wave length range for which
- 10 the anode circuit of the amplifier is aperiodic and for which the amplifier is unstable when the input and secondary circuits are tuned.
- 15
- 20
- 25

My invention resides in a system and apparatus of the character hereinafter described and claimed.

For an illustration of one of the various forms my invention may take, reference is to be had to the accompanying drawing, in which:

- 30 Fig. 1 is a diagrammatic view of a radio receiving system embodying my invention.

Fig. 2 is illustrative of the relations of the transformer windings.

- 35 Fig. 3 is a fragmentary diagrammatic view illustrating a modification.

Referring to Fig. 1, the radiant energy absorbing structure comprises an antenna or equivalent absorbing structure D and the counter-capacity or earth connection E, between which is included the primary P of a radio frequency transformer. It will be understood, however, that other types of energy absorbing structure or circuits may be employed, including looped antennæ or so-called frame aerials.

Inductively related to the primary P is the secondary S, in shunt with which is connected the variable tuning condenser C for effecting tuning in the input circuit of the thermionic device V, of the so-called audion type comprising anode a, grid or control electrode g, and cathode or filament f. The tube V is utilized as a radio frequency amplifier of which there may be but one stage,

but preferably several stages, as two to four or more, as may be suitable or desirable. In the example illustrated, there is a second radio frequency amplifier V for second stage radio frequency amplification in advance of the detector or de-modulator vacuum tube V¹. The filaments or cathodes f of the several tubes receive their current from the battery A, such as a storage battery or dry cells, each filament or cathode being preferably provided with a rheostat or adjustable resistance r for adjusting the magnitude of filament or cathode current, and therefore the degree of incandescence or electron-emissivity. Connected across the terminals of the battery A is the potentiometer resistance R, along which is movable the contact b connected to one terminal of the secondary S and condenser C. In the anode circuit of each of the tubes V is a primary P of a radio frequency transformer and the anode circuit source or battery B, whose positive terminal is connected with one terminal of each of the last named primaries P, and whose other or negative terminal connects with the negative terminal of the battery A and with each of the cathodes f. A condenser K, which may be of large fixed capacity, serves as a radio frequency by-pass around the battery B.

Inductively related to each of the last named primaries P is a transformer secondary winding S, preferably wound in the same direction as the primary P when viewed from the same end, and shunted by a variable tuning condenser C. The grids of the second tube V and the detector tube V¹ are connected to one terminal of the last named secondaries S and condensers C, respectively, and the other terminals of these last named pairs of secondaries S and condensers C are connected by conductor c to the potentiometer contact b, which is similarly connected with one terminal of the secondary S and condenser C in the input circuit of the first tube V. Accordingly, the grids g of all the tubes are subjected to the same uni-directional potential as determined by the position of the potentiometer contact b. As regards current of radio frequency, the secondaries S and their condensers C of the input circuits of the second tube V and the tube V¹ are connected through conductor c and the fixed condenser K¹ with the tube cathodes, the

condenser K^1 being of large fixed capacity and exhibiting very small reactance at radio frequency. Through the conductor c and the connection d one terminal of each of the 5 groups of secondaries S and condensers C in the input circuits of the several tubes is connected to earth or counter-capacity E .

In the grid circuit of the detector or de-modulator V^1 is connected the usual grid 10 condenser C^1 , shunted by a leak resistance R^1 . In the anode circuit of the tube V^1 , between the terminals e and h , may be connected a telephone instrument or the primary of an audio frequency transformer 15 whose secondary is connected to the input circuit of an audio frequency amplifying tube. In the example illustrated a portion only of the battery B is utilized in the anode circuit of the tube V^1 .

20 As well understood in the art, the action in general of the apparatus described is such as to amplify by each of the tubes V the radio frequency current representative of the received signal or message, while the 25 tube V^1 operates to amplify and detect or de-modulate, to produce in its anode circuit an audio frequency current representative of the signal and more particularly representing sound waves or speech.

30 To effect stability of each of the radio frequency amplifiers V , that is, to prevent regenerative action or condition in which instability arises or oscillations are produced, the primary P in the anode circuit 35 has so few turns, or, in general, exhibits such small inductance that with the associated capacity or capacities, and particularly the capacity between electrodes, as anode and grid, within the tube V , the anode circuit, by itself and irrespective of the tunable secondary circuit coupled thereto, is aperiodic; that is, the anode circuit, unaffected by the tunable 40 secondary circuit coupled thereto, is not in resonance or in tune with the radio frequency of the received energy for and throughout a predetermined range of frequencies or wave lengths of the received energy. For example, the natural period of the anode circuit of each of the tubes V as 45 determined or affected by the inductance of the primary P is that corresponding with a wave length of the order of 75 meters, with the result that the tube V will be stable, in the sense that its anode circuit, when unaffected 50 by the tuned secondary circuit coupled thereto, is aperiodic for wave lengths materially greater than seventy-five meters, preventing regenerative or feed-back action or the production of sustained oscillations which, if occurring, disturb and interfere with satisfactory reception.

For the example given, the number of turns of the primary P may be about fifteen, the associated secondary S having about 55 fifty-five or sixty turns, the ratio of trans-

formation therefore being of the order of four, though somewhat smaller and considerably greater ratios of transformation may be utilized, depending on the degree of coupling.

The windings of a transformer of this character are indicated in Fig. 2, the primary P being disposed within the secondary S , and sufficiently spaced therefrom to prevent close coupling and to effect suitable 75 looseness of coupling, whereby the tuning effect of the condenser C in shunt to the secondary S will have influence upon the anode circuit in which the primary P is connected, which is small, or substantially smaller than 80 in the case the windings P and S are closely coupled. By such loose coupling the stability or non-oscillatory condition of the input and anode circuits of the tube in whose anode circuit the primary P is connected is 85 further ensured. By way of example, the conductor of which the primary P and secondary S are wound may be No. 22 Brown & Sharpe gauge copper wire, suitably insulated, as by double cotton; the primary P 90 may be wound on a cylindrical tube or member of insulating material having a diameter of $2\frac{1}{8}$ inches, while the secondary S may be wound upon a form or tube of molded insulating material, as bakelite, three inches 95 in diameter, whereby the primary and secondary coils are spaced from each other about three-sixteenths of an inch, the difference in their diameters being about three-eighths of an inch.

100 The inductance of the primary P in the foregoing example is of the order of 30 microhenries, that of the secondary S is of the order of 220 microhenries, and the mutual inductance, representative of the degree of coupling, is of the order of about 50 microhenries only.

105 A transformer of the design above given by way of example will serve for radio frequency amplifying purposes for wave lengths of the order of 450 meters to wave lengths of the order of 625 meters, when the secondary is tuned to those wave lengths, the 110 number of turns and inductance of the primary P being small, as stated, but sufficient, however, to effectually transfer energy to its associated secondary for wave lengths of the order of 625 meters, there being an upper limit of the wave length utilizable, for with 115 increasing wave length the number of primary turns should increase to effectively transfer energy to the secondary circuit. Tuning the secondary circuit coupled to the anode or primary circuit has the effect to render the tube or amplifier V unstable, because tuning the secondary circuit has a tuning 120 effect upon the anode or primary circuit which tends to make the tube unstable; in the example given, however, when tuning to 450 meters and upward by means of a variable 125 130

condenser, solely, as indicated, that is, without varying the inductance of the secondary circuit, the increase in the capacity necessary for tuning is itself a stabilizing factor.

5 For wave lengths shorter than those of the order of 450 meters, down to wave lengths of the order of 250 meters, a transformer of the design above described does not, when the secondary is tuned to those shorter wave 10 lengths, ensure stability or non-regenerative or non-oscillatory condition. Therefore, to render the apparatus utilizable over a wave length range additional to that for which the transformer design serves to ensure stability, 15 auxiliary stabilizing means of any suitable character may be employed. For example, the potentiometer R^b may be provided, whereby the grids of the several tubes are maintained at suitable potential higher or 20 more positive than the most negative portion of their cathodes or filaments f , thereby introducing losses by the resistance so introduced into the input circuit, and thereby suppressing regenerative action or tendency to 25 oscillations suitable, for example, for the additional wave length range from about 450 meters down to about 250 meters, the shortest wave length of the entire range and of the supplementary or additional range being, 30 however, substantially longer than the wave length, for example, about 75 meters, for which the anode circuits by themselves become resonant or substantially so in virtue of the relatively low inductance of the transformer primaries P connected therein.

In lieu of utilizing a potentiometer for the aforesaid purpose, each of the primaries P , in the anode circuits of the tubes V , may be made adjustable, as indicated in Fig. 3, either 40 by taking out a suitable number of suitably spaced connecting taps, or by rendering the primary continuously adjustable. In such case the primary P will remain the same as before as to total number of turns, and the 45 effect of the adjustment is therefore to reduce the number of primary turns, thereby rendering the anode circuit resonant for shorter and shorter wave lengths. By so adjusting the primary P , as, for example, for 50 wave lengths shorter than of the order of 450 meters, the stable condition as effected by the primary P alone extends into lower wave length ranges, thereby preventing instability or oscillatory condition of a tube V for wave 55 lengths lower than of the order of 450 meters, down to which wave length the tube V is stable when all the turns of the primary P are in circuit.

Or, in addition to the utilization of a primary adjustable as to its number of turns as above described, a potentiometer, as R^b , may be used, thereby further ensuring stability or effecting stability over a still wider wave length range additional or supplementary to the principal wave length range for which

the adjustable primary P by itself ensures stability.

The transformer whose primary P is in the antenna path may be of the structure and design above described with respect to the 70 tube coupling transformers. By so doing, the number of tuning adjustments is reduced to the number of adjustments corresponding with the number of tuning condensers C . It serves also as a matter of convenience in the 75 matter of manufacture, in that all the radio frequency transformers are alike. However, the primary P will render the antenna path or circuit resonant only for a particular wave length or narrow range of wave lengths, and to this extent there is some sacrifice. However, it will be understood that the antenna path may be tuned, if desired, by adding thereto either an adjustable inductance or 80 adjustable capacity, or both.

By recourse to the stabilizing means hereinbefore described, the number of radio frequency amplifier stages utilizable is increased, and three, four or more stages of radio frequency amplification may be resorted to without instability, since each stage 90 is rendered stable and the coupling between stages is loose, or in any event not sufficiently close to effect interaction through a series of stages to produce instability.

While I have described my invention with respect more particularly to short waves, such as now commonly used in broadcast reception, it will be understood that the principles of my invention are applicable 100 also to systems for receiving waves much longer than of the order of 600 or 625 meters, in or of wave length ranges whose shortest wave length is much longer than of the order of 450 meters of the example hereinbefore given.

The stability of the tubes V and their associated input and output circuits is ensured for wave lengths of about 450 meters and upwards, by transformers having the described characteristics, whether or not the tubes and the auxiliary apparatus and connections are assembled closely, as in a receiving unit or set. When not so closely assembled in a compact set, the stability is 110 ensured, by recourse to transformers having the aforesaid characteristics, for an additional or supplemental wave length band or range below 450 meters to say 250 meters 115 or even shorter waves approximating the aforesaid 75 meter waves, at which resonance occurs. But when assembled in a compact unit or set, the close approach to each other of the devices and connections external to the tubes effects undesired couplings, causing 120 parasitic oscillations which will not be prevented by the characteristics of the transformer for wave lengths materially shorter than about 450 meters, but by recourse to 125 the potentiometer R^b , or the tapped or ad-

justable primary, or both, stability is ensured for the lower part of the wave length band or range whose shortest wave length is of the order of 250 meters.

5 As conducive to increase of stability by reduction of capacity or capacitative coupling between the primary and secondary windings P and S, these windings are so related, as indicated in the drawing, that the high 10 potential end of one is adjacent the low potential end of the other. In the example illustrated, that end of the primary P whose terminal connects with the anode is disposed adjacent that end of the secondary S which is simultaneously at low potential. In other 15 words, the primary P is connected in the reverse sense in the anode circuit to the sense in which the secondary S is connected in its circuit.

20 What I claim is:

1. A tuned radio frequency amplifier system comprising a three-electrode thermionic amplifier, means for tuning the input circuit thereof, a radio frequency transformer having its primary in the anode circuit of said amplifier, the secondary of said transformer loosely coupled to said primary, said primary and secondary windings being relatively reversed, means for tuning the circuit of 25 said secondary for a range of wave lengths for which the anode circuit of said amplifier is aperiodic and for which said amplifier is unstable when said input and secondary circuits are tuned thereto, and loss-producing 30 means for maintaining said amplifier stable notwithstanding tuning of said input and secondary circuits throughout said wave length range.

2. A tuned radio frequency amplifier system comprising a three-electrode thermionic amplifier, means for tuning the input circuit thereof, a radio frequency transformer having its primary of low number of turns in the anode circuit of said amplifier, the secondary of said transformer having a number of turns great with respect to the number of primary turns and loosely coupled to said primary, said primary and secondary windings being so relatively reversed that the 40 high potential end of one of said transformer windings is adjacent the low potential end of the other for procuring low capacity coupling between said windings, a second three-electrode thermionic device in whose input circuit said transformer secondary is included, means for tuning said last named input circuit for a wave length range for which the anode circuit of said amplifier is aperiodic and for which said amplifier is 45 unstable when said input circuits are tuned thereto, and loss-producing means in the input circuit of said amplifier for maintaining it stable notwithstanding said input circuits are tuned throughout said wave length 50 range.

3. A tuned radio frequency amplifier system comprising a three-electrode thermionic amplifier, means for tuning the input circuit thereof, a radio frequency transformer having its primary in the output circuit of 55 said amplifier, said primary winding having an inductance of such magnitude that said output circuit is aperiodic throughout a range of wave lengths, the secondary of said transformer loosely coupled to said primary 60 and having a number of turns great with respect to the number of turns of said primary, said primary and secondary windings being relatively reversed, means for tuning the circuit of said secondary for said wave 65 length range for which said amplifier is unstable when said input and secondary circuits are tuned thereto, and loss-producing means in the input circuit of said amplifier for stabilizing it throughout said range notwithstanding said input and secondary circuits are tuned.

4. An unshielded multtube radio receiving set, the approach to each other of whose devices and connections external to the tubes 70 effects undesired couplings, comprising a system of three-electrode thermionic devices at least one of which is a radio frequency amplifier, means for tuning the input circuit of said amplifier, a radio frequency transformer having its primary in the output circuit of said amplifier, said primary winding having an inductance of such magnitude that said output circuit is aperiodic throughout a 75 range of wave lengths, the secondary of said transformer loosely coupled to said primary, said primary and secondary windings being relatively reversed, means for tuning the circuit of said secondary for said wave length 80 range for which said amplifier is unstable when said input and secondary circuits are tuned thereto, the input circuit of another of 85 said thermionic devices including said transformer secondary and said means for tuning it, and loss-producing means in the input circuits of said amplifier and said other thermionic device for effecting stability throughout said wave length range.

5. A tuned radio frequency amplifier system comprising a three-electrode thermionic amplifier, means for tuning the input circuit thereof, a radio frequency transformer having its primary of low number of turns in the anode circuit of said amplifier, the secondary of said transformer loosely coupled to said primary, said primary and secondary windings being relatively reversed, means for tuning the circuit of said secondary for a range of wave lengths for which 90 said amplifier is unstable when said input and secondary circuits are tuned thereto, and means for reducing the inductance of said primary effective in the anode circuit of said amplifier and loss-producing means in the 95 input circuit of said amplifier for stabilizing 100 it throughout said range.

it notwithstanding said input and secondary circuits are tuned throughout said wave length range.

6. A tuned radio frequency amplifier system comprising a three-electrode thermionic amplifier, means for tuning the input circuit thereof, a radio frequency transformer having its primary in the output circuit of said amplifier, said primary winding having an inductance of such magnitude that said output circuit is aperiodic throughout a range of wave lengths, the secondary of said transformer loosely coupled to said primary and having a number of turns great with re-

spect to the number of turns of said primary, means for tuning the circuit of said secondary for said wave length range for which said amplifier is unstable when said input and secondary circuits are tuned thereto, and loss-producing means in the input circuit of said amplifier for stabilizing it throughout said range notwithstanding said input and secondary circuits are tuned.

In testimony whereof I have hereunto affixed my signature this 11th day of January, 1924.

WILFORD C. MACFADDEN.
